UNITED STATES PATENT OFFICE.

WILLIAM G. PRICE, OF NEW CASTLE, PENNSYLVANIA.

BRAKE-RIGGING.

No. 894,853.

Specification of Letters Patent. Patented Aug. 4, 1908.

Application filed November 9, 1907. Serial No. 401,497.

To all whom it may concern:

Be it known that I, WILLIAM G. PRICE, a resident of New Castle, in the county of Lawrence and State of Pennsylvania, have 5 invented a new and useful Improvement in Brake-Rigging; and I do hereby declare the following to be a full, clear, and exact description thereof.

My invention relates to brake rigging for 10 cars or other vehicles.

The object of the invention is to provide for the supporting of the brake-rigging from the equalizer-bars, so as to be entirely independent of the truck-frame, and at the same 15 time provide for the movement of the brake-beam in a substantially horizontal plane.

Another object of my invention is to reduce the brake-shoe pressure on one pair of the wheels of the truck which carry the 20 lighter load.

To these ends my invention comprises the novel features hereinafter set forth and claimed.

In the drawings Figure 1 is a plan view 25 with parts broken away of my improved brake-rigging; Fig. 2 is a side elevation with parts broken away; and Figs. 3, 4 and 5 are details.

In the drawings the numeral 2 designates 30 a suitable truck-frame provided with the bolster 3 and supported on the wheels 4 and 5 secured to the axles 6, 6^a. Equalizer-bars 7 are supported upon the journal-boxes 8 in the usual manner and said journal-boxes are 35 provided with the brackets 9 which support the springs 10. The truck-frame 2 is carried upon the springs 10.

Secured to the equalizer-bars 7 are the 40 brackets 11 and 12. Hangers 15 and 16 are pivoted to the brackets 11 and 12, respectively, and carried by said hangers are the 45 brake-beams 17 and 18. Brake-shoes 19 and 20 are secured to the brake beams 17 and 18, respectively.

The live-lever 21 is secured at its upper end 45 in the jaw 22 by the bolt 23, said jaw 22 being connected to the top brake-rod 24 by the bolt 25. The lower end of the live-lever 21 is connected to the adjustable brake-rod 26 50 and said rod 26 connects the live-lever 21 with the dead-lever 27.

The live-lever 21 has the arms 28 projecting out therefrom and connected to said 55 arms are the reducing-levers 29, said levers being secured to said arms by means of the bolt 30 extending through said arms. The

upper ends of the reducing-levers 29 are connected to the brackets 31 on the brake-beam 17 by means of the bolts 32. The lower ends of the reducing-levers 29 are connected to 60 the brackets 33 which are bolted to the fulcrum bar 34 by means of the bolts 35. The fulcrum bar 34 is riveted or otherwise secured to the angles 36 and said angles are connected to the equalizer-bars 7 by the 65 bolts 37.

The dead-lever 27 bears at its upper end against the hardened steel wear-plate 38, said wear-plate being secured to the angle-beam 39 which is bolted to the transom 40. 70 The dead-lever 27 is provided with the hardened steel insert 41 which rests directly against the hardened steel plate 38. In this manner the wear on the dead-lever is reduced to a minimum and thereby frequent 75 adjustment of the same is obviated.

As the motor is suspended outside of the driving axle 6^a, and there is no motor carried on the axle of the wheels 4, the wheels 5 have to carry a much greater load than the wheels 80 4 and consequently the pressure of the brake-shoes must be much greater upon the wheels 5 than upon the wheels 4. To provide for this difference and in order to secure this reduction in brake-shoe pressure upon the 85 wheels 4 is the purpose of the reducing levers 29 which are fulcrumed at their lower ends on the equalizer bar, or that which is the same thing, upon the fulcrum beam 34 connecting said bars. 90

The reducing levers support the brake beam so as to hold it practically horizontal through its entire range of movement.

The whole brake rigging is entirely independent of the frame, except where the dead 95 lever bears against the transom, and is supported and directly connected to the equalizer bars.

What I claim is:

1. The combination of a truck - frame, 100 wheels, axles, equalizer-bars, a brake operating lever, a reducing lever connected to said lever and fulcrumed on said equalizer bars, and a brake-shoe connected to said reducing lever. 105

2. The combination of a truck - frame, wheels, axles, equalizer-bars, a live-lever, a reducing-lever connected to said live-lever and fulcrumed on said equalizer-bars, and a brake-shoe connected to said reducing-lever. 110

3. The combination of a truck - frame, wheels, axles, equalizer-bars, a live-lever, a

reducing lever connected to said live-lever, a fulcrum beam connecting said equalizer-bars and to which said reducing - lever is fulcrumed, and a brake-beam connected to said 5 reducing-lever.

4. The combination of a truck - frame, wheels, axles, equalizer-bars, a live-lever having arms extending out therefrom, reducing-levers on said arms, a fulcrum-beam connecting said equalizer-bars and to which said reducing-lever is fulcrumed, and a brake-shoe connected to said reducing-levers.

5. The combination of a truck - frame, wheels, axles, equalizer - bars, brackets on 10 said equalizer-bars, a live-lever, a reducing-lever connected thereto, and a brake-beam supported by said brackets and said reducing-lever.

6. The combination of a truck frame, wheels, axles, equalizer-bars, a dead-lever, a 20 brake-beam, the upper end of said lever resting in contact with said frame, and a hardened plate inserted between said lever and said frame.

7. The combination of a truck - frame, 25 wheels, axles, equalizer-bars, a dead-lever having a hardened insert at its upper end, and a brake-beam, the upper end of said lever resting in contact with said frame.

In testimony whereof, I the said WILLIAM 30 G. PRICE have hereunto set my hand.

WILLIAM G. PRICE.
